SPRAY DEVICE FOR PROJECTING MOLTEN PARTICLES

Leo M. Simonsen, Eugene, Oreg.

Application December 17, 1943, Serial No. 514,639

5 Claims. (Cl. 91—12.2)

1

This invention relates to a device for applying powdered metallic, non-metallic or vitreous material in molten spray form to metallic or non-metallic articles to produce a smooth, uniform coating and finish thereto.

In the operation of existing devices of this character, wherein solid, granular, or powdered materials are applied to surfaces by spraying methods, said materials are melted at the tip of the spraying device and the molten material is projected therefrom by means of a gaseous blast in an enveloping flame. The temperature in the usual melting zone of spray guns or devices of this character is critical due to the fact that it must provide a high temperature for sufficient time interval to melt the material but not so long that the material will be burned by the intense heat generated.

Furthermore, in the spraying of metallic materials it is desirable to do so in what is known as a reducing atmosphere in order to avoid excessive oxidation of the molten particles, while on the other hand, in the spraying of certain non-metallic materials, it is advantageous to do so in an oxidizing atmosphere. For example, in the spraying of nickel or chromium powders, a high initial melting temperature is necessary and a reducing atmosphere is desirable. In the spraying of aluminum, zinc, tin, lead, or solder powders, a lower initial temperature is necessary and a reducing atmosphere is advantageous. In the spraying of glass or ceramic glazes, particularly those known as sulphide glazes, a fairly high initial temperature is necessary and an oxidizing atmosphere is desirable, whereas in the spraying of materials known as plastics, in powdered form, a low temperature only is required and either an oxidizing, neutral, or reducing atmosphere is used depending upon the composition of the plastic utilized.

In the use of conventional devices of this character, when a high initial melting temperature is required to melt the powdered material within a given time, there is the danger of overheating the surface upon which the molten metal impinges or adheres. This condition is usually overcome by altering the distance between the gun nozzle and the base upon which said molten metal is to impinge, and by increasing the air pressure behind the molten particles, in which event, there is increased oxidation of the molten material during its trajectory through the flame from the gun nozzle to the base surface. Furthermore, during the spraying of powdered glass or glazing material the preheating of the base surface to a higher

2

temperature than that required to initially melt the glass or glaze, is advantageous to aid in creating a satisfactory bond between the glaze or glass and the base surface and to create a means of creating a uniformly annealed, vitreous coating.

It is an object of the present invention to provide a spray gun having a wide range of adaptability and flexibility to suit varying conditions and materials being applied.

It is a further object of the present invention to provide a spray gun in which, when a higher initial melting temperature is required to melt the powdered material within a given time, there is not danger of overheating the surface upon which the molten material impinges.

It is a further object of the invention to provide a spray apparatus with which, during the spraying of powdered glass or glazing materials, pre-heating of the base surface to a higher temperature and over a larger area than that required to initially melt the glass or glaze, may be obtained.

It is a further object of the invention to provide a spray apparatus in which the powdered metal or non-metal or mixture thereof, is introduced into the flame at a point distant from the gun in such a manner that its melting may take place at a proper time with respect to the base surface.

Other objects and advantages of the present invention will appear from the following description in which the preferred embodiment is set forth in conjunction with the accompanying drawings.

Referring to the drawings:

Fig. 1 is a longitudinal sectional view of a spray apparatus incorporating my invention.

Fig. 2 is a cross-sectional detail taken along the line 2—2 of Fig. 1.

Fig. 3 is a cross-sectional detail taken along the line 3—3 of Fig. 1.

Fig. 4 is a diagrammatic representation of the manner in which the powdered material is fed into the flame and the manner in which it strikes the base surface, together with an elevational illustration of the orifice used.

Fig. 5 is a diagrammatic representation of another manner in which the powdered material may be fed into the flame together with a showing of the manner in which it strikes the base surface, together with an elevational representation of the orifice used.

Fig. 6 is a diagrammatic representation of the manner in which the powdered material may be fed into the flame together with a representation

of the pattern of the powdered material upon the base surface and an elevational view of the orifice used.

Referring to Figure 1, the device consists of a tube 10 of suitable material which is provided with threads 11 at one end and which is slightly tapered at its other end. This tube is slidably fitted within the body 12, as shown, and while it is desirable that the fit be substantially air-tight, it is not absolutely essential inasmuch as suitable gasket means may be provided as will hereafter be explained. Body 12 is provided with a mixing chamber 13 which divides body 12 into two concentric shell or wall portions 14 and 15. Inner shell portion 15 is generally deeper than outer shell 14 and extends forwardly along tube 10 as shown. Chamber 13 is closed by an annular ring-shaped plate 16 which is adapted to fit around shell portion 15 and to abut against the forward face of shell portion 14. Plate 16 is provided with orifices 17 which allow passage of gas from chamber 13.

Tubular member 18 is mounted on body 12 as by means of threads on its inner surface which are adapted to cooperate with threads 19 on shell 15. It will be seen that when tube 18 is mounted upon member 15, it will contact plate 16 and urge it snugly against the forward face of shell 14. A plurality of orifices 20 are provided in member 18 and are arranged preferably in banks of four, although that is not an essential part of this invention.

Tubular member 21, which is of greater diameter than tubular member 18, is mounted upon outer shell 14 and is concentric with respect to tubular members 18 and 10. Cooperating threads on members 14 and 12 provide means whereby they may be united or separated at will.

I have provided a circular plate 22 the outside diameter of which is substantially equal to the inside diameter of tube 21. Plate 22 is provided with two concentric rows of orifices 23 and 24 respectively, and on its rear face, with a circular groove 25 concentric with and lying between said concentric rows of orifices. Circular groove 25 is adapted to accommodate and locate the adjacent end of the tubular member 18. Plate 22 is also provided with a centrally located threaded orifice 26.

A nozzle or tip 27 is likewise threaded and is adapted to cooperate with the threads in centrally disposed orifice 26 whereby the nozzle may be removed or replaced at will. Tip 27 is bored to snugly fit about the adjacent end of tube 10, without however interfering with adjustment of the latter.

Circular plate 22 is maintained in its position by means of interior annular flange 28 on member 21. When member 21 is mounted upon member 14, flange 28 is urged against the outer face of member 22 and plate 22 is thereby gripped between flange 28 on member 21 and the forward end of member 18, which lies in circular groove 25.

Generally surrounding the nozzle 29 there is an inwardly flaring annular tip 29 which is adapted to be threadedly engaged on the forward end of member 21 as shown.

Radially extending nipples 30 and 31 having corresponding orifices 32 and 33 are threaded in order that chamber 13 may be suitably connected to a source of oxygen or air and a suitable fuel gas.

Means is provided for adjusting the position of tube 10 relative to the body and the nozzle 27.

Thus I have provided annular flange 34 on the rear end of member 12. A suitably flanged ring 35 engages flange 34 and is secured by means of bolts 37 to a nut 38. This nut together with lock nut 38 engages threads 11 on member 10 to retain tube 10 in an adjusted position.

As has heretofore been pointed out the slideable connection between members 10 and 12 should be as gas-tight as possible. In the event machine operations do not permit a thoroughly gas-tight connection to be maintained, suitable gasket or bushings may be utilized in any suitable manner.

Operation of my device may be briefly described as follows: Tube 10 is connected to a suitable source of air under pressure. Suitable means is provided for feeding the material to be applied, in powdered or granular form, into the air stream, whereby a constant flow of air with divided solids 20 homogeneously distributed therein is maintained through tube 10.

Chamber 13 is likewise connected by means of orifices 22 and 23 to a suitable source of air or oxygen or a mixture of air or oxygen, and any natural or artificial fuel gas desired. These gases, coming in at an angle of 90° to each other are thoroughly mixed, and the curved rear surface of chamber 13 assists materially in the mixing operation and also in projecting the gaseous mixture forward. The gaseous mixture passes through orifices 17 in plate 16 into the chamber between members 18 and 21. A portion of this mixture will pass through orifices 20 into the chamber between members 18 and 10. Gas from both of these chambers will then be forced through orifices 23 and 24 respectively, at which point they are ignited, and create a plurality of flame jets as shown in Figs. 4, 5 and 6. The jets from orifices 23 are somewhat larger than from orifices 24 because the latter are smaller and because the pressure within the chamber defined by tubes 21 and 18 is slightly greater than the pressure within the chamber defined by tubes 10 and 18. The material-laden air is discharged from tube 10 and nozzle 27 into this general flame formed by the intermerging jets. The pattern assumed by the finely divided material being projected will depend upon certain factors, including the distance between the discharge end of tube 10 and the discharge end of nozzle 27. When these parts are relatively far apart as shown in Fig. 4, the pattern assumed by the finely divided material is that of a cone somewhat as illustrated and the finely divided material is dispersed accordingly. When the two discharge orifices are positioned relatively close together as shown in Fig. 5, the pattern assumed by the discharged material is more limited and the pattern is more compact as the finely divided material is not so widely dispersed.

The reason for the above is that for the retracted position of Figure 4 the spread of the discharging jet is determined largely by the convergent orifice in nozzle 27, whereas for the position of Figure 5 the discharging jet assumes some of the characteristics of a jet discharging from an extended cylindrical orifice. It is well known that an air or gas jet issuing from the end of a converging orifice tends to spread over a wider area than a jet issuing from an extended cylindrical orifice (assuming like effective flow areas and pressures) due to the lesser efficiency of the former, to the attendant turbulence of the issuing air stream, and to the tendency of the stream to be slightly contracted in a region near the dis-

charge end of the nozzle, beyond which region the stream tends to expand.

By employing natural or artificial gases such as propane, butane, acetylene, etc., in combination with air or oxygen, a wide variety of flame temperature is possible. Also by varying the volume of either the natural or artificial gas in relation to the volume of air or oxygen employed an oxidizing or reducing flame is obtained thus fulfilling one of the objects previously mentioned herein. By increasing the pressure of both gas and air and assuming the same volume ratio, a longer flame is obtained between the gun nozzle and the base plate on which the material is to be deposited. By providing this type of adjustment, a range of from high to low temperature near the nozzle, a sustained range of from high to low temperature throughout the flame trajectory, and a variable flame length, each part of which can be an oxidizing, neutral, or reducing atmosphere as desired, are all obtained.

As previously pointed out, by altering the longitudinal relationship between the discharge ends of tube 10 and nozzle 21, it is possible to obtain a variable length of material cone in either an oxidizing or reducing temperature created by the flame. It should also be noted that by varying the quantity of powdered material to that of the entraining air, a further adjustment is possible, and in some instances it is necessary, particularly in consideration of the latent heat of fusion of various metals and their specific gravity. As an example, a powdered metal with a high latent heat of fusion and a high specific gravity will require a low feed rate and a high air pressure in order to permit the suspension of the particles in the air. This condition automatically calls for a fuel of high calorific value in combination with oxygen in order to maintain a melting temperature commensurate with the latent heat-melting time function, whereas a material having a low latent heat of fusion and low specific gravity may be readily floated with low air pressure and readily melted in a flame of natural gas and air.

Further control of the flame is obtained by the type of tip 29 which is employed. The tip may be either a straight tube acting merely as a continuation of tube 21, which is in reality the outer shell of the gun body, or it may be flared inwardly or outwardly at varying degrees depending upon the shape of the flame desired. For example, a tip flared inwardly as shown in Fig. 1 will yield a concentrated flame body which is necessary particularly in the spraying of high melting point powders where a highly localized preheating of the base surface upon which the powder is to be applied is advisable and where an excessively large preheated area is not necessary. On the other hand, in the event one is spraying glass and glazing powders, in which case a lower initial melting temperature is required and an enlarged preheated area is essential (particularly in the application of spraying glass in connection with repair work), an outwardly flaring tip would be more satisfactory.

It has already been pointed out that the relationship between the exhaust orifices of tube 10 and nozzle 21 control the path of the entrained material. For example, a nozzle flaring inwardly as shown, the orifice of which is circular, will yield a circular material feed into the flame the diameter and length of which will be determined by the position of the two orifices. On the other hand, in the event the orifice is square, or sub-

stantially rectangular as shown in Fig. 6, the pattern of the entrained material upon the base to which it is being applied will be substantially similar thereto. Generally speaking, therefore, it may be said that the pattern of the material upon the base will conform generally to the type of orifice in the nozzle 21. Furthermore, it may be pointed out that the size of the pattern upon the base will be a function of the distance between the exhaust nozzle of tube 10 and nozzle 21, that is, the greater the distance between these two orifices, the larger the pattern, assuming the distance from the base remains the same.

It has previously been pointed out that I provide a plurality of concentric rows or orifices 23 and 24. The purpose of the inner row of orifices is to produce flame as close to nozzle 21 as is feasible. In this manner the entrained material is placed directly into the flame and a nearly solid shaft of combustible gases is obtained. Lack of this particular inner row of orifices is noticeable in the case where the outer flame ring alone is used in combination with a short material feed cone, in which a satisfactory pre-heated base surface is obtained coupled with a short material cone of insufficient length to properly apply the material to the base plate unless the gun is held excessively close to the base plate. It will be recalled that it is desirable to inject the entrained material into the flame as early as possible, provided, however, that the flame can be controlled. I have provided ample means of control, for example, the two circular rows or orifices 23 and 24, the inwardly or outwardly flaring tip 29, a particular form of nozzle 21, and the method of increasing or decreasing gas pressure in chamber 13.

I claim:

1. In a device for spraying molten particles of material upon a surface to provide a coating thereon, a nozzle from which said material is discharged, a tube communicating with said nozzle and adapted to convey a stream of said material entrained in air, means for creating a zone of flame concentric with said nozzle and extending from said device to said surface, and means for controlling the trajectory of said particles through said zone of flame comprising means for controlling the distance between the discharge end of said nozzle and the adjacent discharge end of said tube.
2. In a device for projecting particles of material upon a surface to provide a coating thereon, a tube adapted to receive a stream of particles entrained in air, a nozzle communicating with said tube, means for creating a zone of flame surrounding the nozzle and extending between said nozzle and said surface, a tip generally surrounding the discharge end of the nozzle and serving to determine the spread of the flame pattern on the surface, and means for controlling the trajectory of particles being discharged from the nozzle when the gun is disposed in operative position relative to said surface.
3. In a device for spraying molten particles upon a surface to be coated, a particle discharge nozzle, means for supplying to the nozzle a stream of particles entrained in air, a plurality of concentric chambers, orifices serving to connect said chambers, means for supplying a combustible mixture of fuel gas to the outer one of said chambers, and a member surrounding said nozzle and having separate concentric groups of orifices communicating with said chambers, flame jets from said last named orifices serving to form a

composite flame to receive particles projected from the nozzle.

4. In a device for discharging molten particles of material upon a surface to provide a coating thereon, a nozzle through which said particles are discharged, means for creating a zone of flame concentric with said nozzle and extending from said device to said surface, whereby said particles will pass through said zone of flame and be melted thereby, and means for controlling the trajectory of said particles between said nozzle and said surface comprising a tube having a discharge orifice through which said particles pass, the discharge end of said tube being mounted in said nozzle and longitudinally movable with respect thereto, and means for longitudinally adjusting said tube with respect to said nozzle.

5. In a device for spraying molten particles of material upon a surface to provide a coating thereon, a nozzle through which said material is discharged, means for creating a zone of flame concentric with said nozzle whereby said particles will pass through said zone of flame and be melted thereby, a tube communicating with said nozzle and longitudinally movable with respect

thereto, said tube adapted to carry particles entrained in gas, means for controlling the distance between the discharge end of said nozzle and the discharge end of said tube to adjust the pattern of said particles upon said surface for a given location of the device relative to said surface.
